UNITED STATES PATENT OFFICE.

TRUMAN E. AUSTIN, OF BINGHAMTON, NEW YORK.

COMBINED SPARK ARRESTER AND EJECTOR.

SPECIFICATION forming part of Letters Patent No. 512,145, dated January 2, 1894.

Application filed February 15, 1893. Serial No. 462,381. (No model.)

To all whom it may concern:

Be it known that I, TRUMAN E. AUSTIN, of Binghamton, in the county of Broome and State of New York, have invented certain new and useful Improvements in a Combined Spark Arrester and Ejector, of which the following is a full, clear, and exact description, reference being had to the accompanying drawings, which form part of this specification, and in which—

Figure 1 is a side elevation of a locomotive engine provided with my improvements, parts of said engine being shown in longitudinal section for the purpose of showing details which would otherwise be concealed. Fig. 2 is a plan view of the same with the upper part of the smoke-arch broken away. Fig. 3 is a front elevation of said engine with the front of the smoke-arch open. Fig. 4 is an enlarged side elevation of the forward portion of said engine, with parts shown in longitudinal section; and Fig. 5 is a side elevation of part of the front end of the boiler, part of the side of the smoke-arch being broken out for the purpose of showing certain modifications.

This invention relates to improvements on the invention for which Letters Patent of the United States No. 500,648 were granted to me July 4, 1893; and the object of my present invention is to render my former one more effective in its action and to remedy certain slight defects therein.

Experience has developed the fact that small particles of grit and cinder are liable to enter the nozzle of the steam-blast pipe and thence into the steam-chests to effect considerable damage by cutting the faces of the slide-valves and valve-seats; said particles working their way into the steam-chests even when said blast-pipe is provided with an automatic check-valve that is arranged to close whenever the steam-pressure is removed from the interior of said pipe; but I find that, by leading the steam-blast pipe from a steam-passage between the throttle-valve and a piston of the engine—running the end of the blast-pipe into the passage, closing the inner end of said blast-pipe, and finely perforating the portion of the latter that extends into said passage with holes which are too small to allow the particles of grit to pass through them—I

can entirely remedy the danger of cutting the valves and valve-seats without detracting from the efficiency of the steam-blast.

By arranging the cinder-pipe as herein shown and described, I avoid a disagreeable rumbling noise that is produced by arranging the cinder-pipe a short distance from the ash-pan and discharging the cinders into an opening in the front of the ash-pan; and by substituting an adjustable diaphragm for a portion of the screen nearest the front tube-sheet, I can adjust the over-draft through the smoke-arch as occasion may require.

As represented in the drawings, A designates a locomotive boiler of a common and well-known form, none of the internal parts of the fire-box of the same being shown, they not being affected by my invention.

B designates the smoke-arch formed in the forward end of the cylindrical portion of said boiler. A smoke-stack, 1, is erected on the outer side of said smoke-arch for the purpose of carrying off the lighter products of combustion. Within said smoke-arch the usual branch steam-pipe, 2, is arranged to communicate with the steam-chests of the engine cylinders. Exhaust-nozzles, 3, lead from the exhaust passages of said cylinders and are arranged to discharge directly into the base of said smoke-stack.

The above described details of construction form no part of my invention.

C designates a forwardly-inclined screen which has its upper edge connected to the front tube-sheet of the boiler, and its lower edge attached to the upper edge of an imperforate diaphragm, D, which forms the lower part of said screen. The screen C permits an over-draft from the boiler-tubes to the smoke-stack 1. The space 4, between the lower part of the diaphragm D and the shell of the smoke-arch, forms an under-draft between said boiler-tubes and smoke-stack. The over-draft opening can be regulated as occasion may require, and for that purpose I have devised two different arrangements which attain the same end; as shown in Figs. 1, 2, and 4, the means for regulating said over-draft consists of a sliding-plate, E, which is fitted to slide over the lower part of the screen C, guides, 5, being arranged for guiding and supporting said plate; a link, 6, connects the

sliding-plate E with an arm, 7, secured to a rocker-shaft, 8, arranged transversely through the smoke-arch B. On one end of said rocker-shaft an arm, 9, is secured, and a rod, 10, is jointed to the arm 9 for the purpose of rocking said shaft; the opposite end of said rod is provided with a handle, 11, and with a notched-portion, 12, which is fitted to engage on a catch-piece, 13, attached to the boiler A or other convenient part where it will be accessible to the engineer.

In Fig. 5 I show a modified form of device for regulating the opening for the over-draft, the same consisting of a damper or swinging-plate, F, that is hinged to the upper edge of the diaphragm D, so as to be swung toward the screen C, or turned away to a greater or less degree, as occasion may require. To the hinge-pin 14, of said damper an arm, 15, is secured, and a rod, 16, is jointed to said arm for the purpose of turning said damper when required; the opposite end of said rod may be provided with means, like those shown and described for the rod 10, or any other suitable provision for locking the damper F in any desired position in its movement.

H designates a pendent cinder-pocket, and H' the blast-pipes leading from the exhaust-passages of the steam-cylinders; said cinder-pocket and pipes are fully described in the specification, of my former patent above referred to, and a further description of them is unnecessary.

G designates the steam-blast pipe which is preferably arranged to lead from a steam-passage, 17, that leads into the steam-chest of one of the engine-cylinders, but said blast-pipe may be arranged to lead from any steam-passage between the throttle-valve of the engine and either of the slide-valves, the essential point to be observed being that the opening of the throttle-valve shall allow a current of live-steam to pass through said blast-pipe into, and transversely through, the cinder-pocket H. The end of said blast-pipe leading into said cinder-pocket is provided with a nozzle, 18, whose outlet has a reduced diameter in comparison to the bore of said blast-pipe; the inner end of said blast-pipe—which is preferably reduced in diameter—preferably leads from the side of the steam-passage 17, said blast-pipe being kept clear from the bottom of said passage, as shown in Fig. 1, so that nothing but dry steam alone will flow into the blast-pipe. The reduced inner end of said blast-pipe, as shown in Fig. 4, is designated as 19, and its end is closed by a screw-plug, 20, to stop the flow of steam at that point into said blast-pipe, but the periphery of said pipe is finely perforated to prevent the escape of any gritty particles from said pipe. A check-valve, 21, which is arranged to lift when the steam is flowing into the perforated reducer 19, is placed in the pipe G near the passage 17, and, between said check-valve and nozzle 18, there is connected a branch steam-pipe,

22, which leads from the steam-pipe of an air-compressor, I, by which the air-brakes are provided with compressed-air. A stop-valve, 23, is arranged in the steam-pipe of said air-compressor in such manner that when said stop-valve is opened—to start the air-compressor I, a current of steam will flow through the pipe 22 so as to prevent any particles of cinder from closing up the orifice of the nozzle 18.

J designates the cinder-pipe which leads from the after side of the cinder-pocket H toward the ash-pan K; said cinder-pipe is arranged diametrically opposite to the nozzle 18, so that a current of steam escaping from said nozzle will enter said cinder-pipe to force the cinders contained in the latter out of the open end of it, and thence through a pipe L, into said ash-pan. The pipe L—which is considerably larger in diameter than the cinder-pipe J, so as to leave an open annular space between the two pipes—projects from the forward side of the ash-pan K, and the open end of the cinder-pipe J extends slightly into the open end of the pipe L so that, when a current of steam mixed with cinders is discharged from the cinder-pipe J, a volume of atmospheric air will be carried through said annular space to furnish oxygen to promote the combustion of the fuel in the fire-box. By carrying the commingled steam, air, and cinders into the ash-pan K through the pipe L, the disagreeable rumbling sound—caused by the impingement of the commingled currents against the edges of the opening in the front end of the ash-pan—which was observable in my earlier device, is entirely destroyed.

M designates a netting or screen which is attached to the lower edge of the diaphragm D and inclines upwardly and forward to the front end of the smoke-arch B and is joined to the top of the latter; said netting forms a screen whereby sparks, carried through the space 4 or under-draft, will be arrested and thrown down to pass into the cinder-pocket H ready for their discharge through the cinder-pipe J, as above described.

What I claim as my invention, and desire to secure by Letters Patent, is—

1. In a spark-arrester the combination of a netting-screen whose upper edge is connected to the front tube-sheet of a boiler and having its lower edge connected to an imperforate diaphragm; said netting and diaphragm inclining downward and forward from said tube-sheet and the netting forming an over-draft opening between the forward end of the boiler-tubes and the smoke-stack, an imperforate plate arranged to be adjustable for covering over said netting so as to increase or diminish said over-draft, an under-draft opening between the lower edge of said diaphragm and the bottom of the smoke-arch, and a netting connected to the lower edge of said diaphragm and extending upward and forward to the front and top of the

smoke-arch, as and for the purpose herein specified.

2. In a combined spark-arrester and ejector, a steam-blast pipe extending into a steam-
5 passage of the engine; the inner end of said blast-pipe being closed and the inwardly-projecting portion of said pipe being kept clear from the bottom of said steam passage and finely perforated, the opposite end of said
10 blast-pipe being provided with a blast-nozzle which will inject a current of steam transversely through the cinder-pocket, as and for the purpose herein specified.

3. In a combined spark-arrester and ejector, the combination of a cinder-pocket, a steam-blast pipe arranged to discharge steam in a transverse direction through said cinder-pocket; said blast-pipe being provided with a check-valve arranged to open under a
15 pressure of steam coming from a steam passage of the engine, a branch steam-pipe connected to said blast-pipe between the discharge nozzle and check-valve of the blast-pipe, and a steam-stop valve arranged to shut
20

off the flow of steam into said branch-pipe, as and for the purpose herein specified.

4. In a combined spark-arrester and ejector, the combination of a cinder-pocket, a steam-blast pipe arranged to discharge steam in a transverse direction through said pocket, a cinder-discharge pipe leading from said pocket and having its forward end arranged directly opposite to the discharge end of said blast-pipe, an ash-pan under the fire-box of the boiler, and a pipe having its forward end 30 constantly open to the atmosphere and its opposite end attached to and opening into the forward side of said ash-pan and extending in range with said cinder-discharge pipe; the latter being smaller than the open-ended 35 pipe so as to form an annular air opening between the two pipes, as and for the purpose herein specified.
